UNITED STATES PATENT OFFICE

GUSTAV MAIER, OF SCHRAMBERG, GERMANY

FOLDING BOX

Application filed October 22, 1928, Serial No. 314,183, and in Germany October 24, 1927.

This invention relates to folding boxes particularly made of pasteboard, board carton or like materials, the interlocking joints of which being made of tongues punched out of the material of the box and engaging slits of adjacent parts of the same. Folding boxes of said kind may be laid flat for purposes of being packed, or for transit, or the like, and only require finally mounting together when 10 they are brought to the place of using them. The principal feature of such an arrangement is that the construction of the box may be quickly and easily carried out and at the same time an interlocking arrangement is obtained 15 which may be relied upon against any undesired loosening of the interlocking means.

One object of the invention is to provide a folding box capable of meeting said requirements and being characterized by the fact 20 that a member or nose has been pressed out of the tongue serving as a stop which abuts against the edge of the slit so that the arresting of the tongue in the slit will be securely effected. Thus in accordance with the invention 25 a suitable abutment action of said member or nose pressed out of the tongue will be obtained by providing a cut in the stop edge of said member by means of which a sharply edged limitation will be given to said member 30 so that a safe abutment effect in face of the edge of the slit will be secured.

Another mode of carrying out the invention consists in that the cut serving for engaging the tongue trapezoidally projects with its 35 intermediate part which after the introduction of the tongue serves as an abutment for the member pressed out of the tongue and the pressed out member of the fastening nose is situated behind the base line of the tongue. 40 By means of this arrangement a greater security against the danger of the tongue breaking over in the longitudinal direction of its base line will be obtained.

A further more advantageous mode of 45 carrying the invention into practice consists in that on the tongue as well as on the abutment edge of the introduction slit members or noses are pressed out and projecting in opposite directions. Thus by a relatively 50 small depth of pressing out and therefore a

small straining of the fibres of the material a suitable stopping effect and reliable security will be obtained.

The invention may also be used in connection with other known kinds of fastening methods, for example, in such a manner that the tongue is provided at the one side of its base with an incision and adjacent to its other side with a nose pressed out in accordance with the invention. By this means the slit 55 serving for the introduction of the tongue may also be produced by a simple cut. For the purpose of facilitating the introduction of the tongue into the cut the latter may be, according to the invention, extended at its 60 ends beyond the width of the tongues. Said extension may be made either rectilinear or consist of circular cuts or notches made in the corners of the introductory slit. By this 65 means an easy spreading out of the slit during introducing of the tongue will be effected and security against tearing in of the corners of the tongue is given as the bending up of the corners of the slit does not take place directly beside the side edges of the tongue but 70 along a straight or curvilinear, laterally disposed extension of the slit.

In constructing folded boxes provided with the new interlocking means special shifting movements of the walls of the box do not need 75 to be carried out. The assembling of the interlocking parts may be carried out without any tool at least just as rapidly as, for example, by stitching them together by means of a machine, so that the box is particularly 80 suitable for the packing up of goods made in manufactures of blotting products or the like. A further advantage consists in the fact that the interlocking parts may be created simultaneously with the punching out of 85 the cartons forming the box during one and the same step of operation.

Another essential advantage consists in the 90 fact that the nose-like member with regard to its formation by pressing it out of the face 95 of the tongue, possesses a certain elasticity which facilitates the insertion of the tongue into and through the incision of the neighbouring side flap. Moreover the nose-like member offers the advantage that with re- 100

gard to the fact that the abutment is formed by means of the edge of the member projecting freely out of the level of the carton, any tendency of widening the slit after the tongue 5 has been inserted, is avoided, so that no tearing up of the ends of the slit can enter.

In the accompanying drawing several modes of carrying out the invention into practice are shown.

10 Figure 1 is a perspective representation of a folding box the cover part of which being removed.

Figure 2 is a plan view of the interlocking arrangement of the corners made before assembling.

Figure 3 shows in a sectional view a similar corner interlocking arrangement after assembling.

Figures 4 and 5 represent modes of constructing the corner interlockings provided with two pressed out members.

Figure 6 is a sectional view of the interlocking parts after assembling.

Figures 7 and 8 are further examples of 25 constructing the corner joints.

Referring specially to Figures 1, 2 and 3 of the drawing the transversal walls 1 of the box are provided with tongues formed by accordingly punching out the edge of said walls 30 during one and the same step of operation. Each tongue has in the direction of its base line 4 a short cut 5 by means of which sharply edged abutment faces are formed on the rear of the arresting nose 6 pressed out in the 35 tongue.

A slit 7, ordinarily produced by a simple cut, is provided in the opposite folded joint part 2 for engaging the tongue 3. As soon as the tongue 3 has been introduced into the 40 slit 7 the nose 6 with its rear edge, lying in the slot 5, forms a reliable stop in face of the cut edge of the slit 7 and prevents the loosening of the interlocking parts.

According to Figures 4 and 5 the tongue 3 45 is provided with a nose 6 and the cut 7 in the folded joint part 2 has a nose 8. Thus a particularly reliable securing of the interlocking joint against loosening will be obtained as represented by Figure 6.

50 In the afore described mode of constructions the introductory slits 7 are provided on their ends either with semicircular incisions 9, Figure 4, or with circular cuts 10, Figure 5, for the purpose of facilitating the spreading out of the slits during the introduction of the tongues and to prevent the tearing in of the slits at the corners of the same.

Figure 7 shows an interlocking joint 2 having an angular slit 11 with a projecting 60 intermediate part. In this case the nose 6 is situated in the rear of the base line 4 of the tongue 3 in a corresponding distance of about the length of the projection in said slit.

Figure 8 shows how the tongue 3 is provided near its one end with a nose 6 and on

its other end with an incision 13 forming a free corner 12 on the tongue. In this case after completed introduction of the tongue 3 into the slit 7 the rear limiting face of the nose 6 as well as the free tongue corner 12 which bends upwardly during the tension of the carton lies closely on the abutment edge of the slit 7.

Instead of providing the new interlocking joints at the corners of folding boxes made of board carton, they may be, of course, situated at other points of the walls, bottoms or covers of the same. Moreover several abutment noses may be pressed out on the tongues.

What I claim as new is:—

1. Folding box comprising interlocking joints consisting of tongues inserted into and through slits of the side flaps and provided with a nose-like member pressed out of the face of the tongue and forming a hump of about semi-globular shape projecting out of the level of the carton and adapted when the tongue is inserted into the slit to form by means of its free projecting arched edge an abutment for the tongue in said slit.

2. Folding box comprising interlocking joints consisting of tongues provided with a nose-like member of about semi-globular shape, adapted when the tongue is inserted into the slit of the neighboured side flap, to form by means of its free projecting edge an abutment for the tongue, the abutment edge of the said slit having a similar nose-like member pressed out of the face of the said side flap and projecting when the tongue is inserted into the said slit, with its free edge in the opposite direction to that of the nose-like member of the tongue.

3. Folding box comprising interlocking joints consisting of tongues inserted into and through slits of the side flaps and provided on the base at one side of the same with an incision and near the opposite edge with a nose-like member pressed out of the face of the tongue and forming a hump of about semi-globular shape having an arched edge projecting freely out of the level of the tongue.

In testimony whereof, I have signed my name to this specification at Stuttgart, Germany, this 8th day of October, 1928.

GUSTAV MAIER.
